Putnam Putnam of Bell

UNITED STATES PATENT OFFICE.

AUGUSTUS HECK, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING-MACHINE.

1,295,988.

Specification of Letters Patent.

Patented Mar. 4, 1919.

Application filed November 9, 1915. Serial No. 60,596.

To all whom it may concern:

Be it known that I, AUGUSTUS HECK, a citizen of the United States, residing at Springfield, in the county of Hampden and State of Massachusetts, have invented certain Improvements in Wrapping-Machines, of which the following description, in connection with the accompanying drawings, is a specification, like reference characters on 10 the drawings indicating like parts in the several figures.

This invention relates to machines designed to fold a band, label, or other sheet of wrapping material (hereinafter for convenience referred to as a wrapper) about an article and aims particularly to facilitate the application of adhesive material to the wrapper and to the provision of mechanism that will fold the wrapper about the article 20 tightly. More specifically the invention aims to improve the machine shown and described in Patent No. 1,006,081, granted October 17, 1911. The invention will be readily understood from the following description when read in connection with the accompanying drawings, and the novel features will be pointed out in the appended claims.

In the drawings,

Figure 1 is a side elevation of a mechanism embodying this invention, certain of the parts being shown in sections;

Fig. 2 is an elevation of the side of the mechanism opposite to that shown in Fig. 1;

Figs. 3 and 4 are diagrammatic views showing different steps in the wrapping operation; and

Figs. 5 and 6 are perspective views of a package showing the method of wrapping.

The machine shown in the patent above designated has found a substantial market in the wrapping of small articles, such for instance, as cakes of chocolate. These articles usually are inclosed in an inside wrapper, forming a package substantially as indicated at P in Fig. 5, and the package so produced is then inclosed in or encircled by a wide band or wrapper W, Fig. 5. The machine shown in the patent above mentioned is designed to perform both of these wrapping operations but in the accompanying drawings a mechanism for performing the second operation only is shown. As fully explained in said patent, the articles to be wrapped are advanced through the machine

step by step by means of pusher arms, two of which are designated in Fig. 1 by the numerals 13 and 14, these numerals being also employed in the patent to designate the corresponding members. The right-hand arm 13 as shown in Fig. 1 moves one of the articles P from the wrapping mechanism (not shown) through the channel 10 into engagement with the outside wrapper W, which is delivered through the chute 40 into a position across the path of travel of the articles; and this arm then carries this article into the pocket of a tumble box 51. This operation folds the wrapper W partly about the package P. The operating mechanism for the tumble box then gives it a half rotation in the direction indicated by the arrow in Fig. 1, thus bringing the article with the wrapper partially folded about it into the position in which it is shown in said figure and leaving the package substantially in the condition in which it is shown in Fig. 5. The pusher arm 14 next ejects this package from the tumble box carrying it into another channel 16, the top plate of which 80 channel folds the flap f of the wrapper over into the position in which it is shown in Fig. 6. While the pusher arm 14 is ejecting the package in this manner, the arm 13 is pushing another package into the tumble 85 box and both arms then swing downwardly and return to the positions in which they are shown in Fig. 1 in the manner fully described in the patent above designated.

It sometimes happens that the wrapper 90 flap f sags while the arm 14 is ejecting the package from the tumble box and that consequently the wrapper is folded over the package in a loose or wrinkled condition. While the package is in the position in which it appears in Fig. 1, a glue tank 74 carrying a glue applying roll 81 is swung downwardly to bring the roll into contact with the margin of the flap f and apply a strip of adhesive to it as indicated at g in 100 Fig. 5. In some cases, particularly where the flap f is short, due for instance to the fact that it is desired to have the lap in the wrapper come substantially in the middle of the upper face of the package, it is difficult to arrange the parts so that the roll 81 will always apply glue to the flap in the desired manner. The present invention provides a construction in which both of the objections just described are overcome.

The mechanism so far described is substantially like that shown in the patent above named. Power is applied to the driving shaft 20 of the machine in any convenient manner and this shaft carries a bevel gear 21 that meshes with another gear on a shaft 22 to which is fixed the driver 24 for a Geneva wheel 25 mounted on another shaft 26 that is mounted above and parallel to the shaft 22. This shaft 26 also has fast thereon a gear 27 that meshes with a gear 28 fast on the shaft 29 which carries the tumble box 51. This driving mechanism gives the tumble box the intermittent rotating movement above mentioned.

When the tumble box 51 rotates into the position in which it is shown in Fig. 1, the flap *f* of the wrapper *W* swings into contact with a roll 30 mounted to rotate in suitable bearings carried by a small bracket 31 that is supported by the machine frame. While the flap rests on this roll, the glue tank 74 is swung down far enough to bring the roll 81 against the flap *f* at a point opposite the point at which it is supported by the roll 30. The flap thus is grasped or pinched between these two rolls. The supporting and operating mechanism employed to give the tank 74 this movement comprises an arm 77 that is supported by a rock shaft 78 and supports the tank on its free end. The free end of another arm 79 secured to the rock shaft 78 bears on a bolt 86 that is adjustable on the upper end of a post or rod 87 mounted to slide vertically in a guide supported by the machine frame. The lower end of this rod 87 carries a roll that runs on the periphery of a cam 88 mounted fast on the shaft 20. This operating mechanism gives the tank 74 and the roll 81 which is journaled in the bottom of the tank an oscillating movement in the arc of a circle about the axis of the shaft 78 as a center. Part of the periphery of the roll 81 is exposed through a slot in which the roll fits snugly at the bottom of the tank 74 and during the upward movement of the tank this roll is rotated in order to expose a freshly glued surface to the flap *f* upon the next downward movement of the tank. For this purpose the shaft 84 on which the roll 81 is mounted is provided at one end of the tank with a ratchet wheel 83 that meshes during the upward movement of the tank with the teeth of an arm 85 that is pivotally mounted and is yieldingly held against the wheel by a spring (not shown). This construction while slightly different in details is, in all substantial particulars, like that shown and described in the patent above designated. A pawl 83' prevents reverse rotation of the roll 81.

While the rolls 30 and 81 are gripping the end of the wrapper flap *f*, a folder bar 33 is moved into contact with the flap be-

tween the article and the point at which it is gripped by said rolls and tensions or tightens this flap. This bar connects the ends of a bifurcated lever 34 fulcrumed at 35 and connected by a link 36 with one end of a lever 37 which is fulcrumed on the rock shaft 38 and carries a roll 39 that runs on the periphery of a cam 40 fast on the shaft 20. A spring 41 encircles the link 36 and acts on said link in a direction tending to hold the bar 33 in the receiving end of the channel 16; or in other words, directly in front of the package positioned in the tumble box 51 and just below the middle portion of the flap *f*. The cam 40 next operates through the connections just described with the lever 34 to swing the folder 33 from the position in which it appears in Fig. 1 into that in which it is shown in Figs. 3 and 4, where it becomes operative to tension the flap *f* in the manner above described. The folder 33 is now positioned just above the path of the ejecting movement of the package *P* and as the pusher arm 14 moves through the pocket in the tumble box 51 to eject the package, pushing it from the position shown in Fig. 3 to that shown in Fig. 4, the package slides under the folder 33 which swings the flap *f* upwardly across the front face of the package and then moves this flap over on to the top of the package as the ejecting movement continues. The roll 81 is moved away from the roll 30 just before the flap *f* is pulled out from between these two rolls so as to avoid the smearing of glue on the roll 30 and also to avoid applying glue too close to the edge of the flap. The small roll 42 positioned at the lower side of the receiving end of the channel 16 and directly under the folder 33 facilitates the ejecting movement of the package. This folding operation lays the glued end of the flap on to the end already folded and completes the wrapping operation, leaving the package in the condition in which it appears in Fig. 6.

It is obvious that the adjustment of the parts will depend largely upon the material from which the wrapper is made, the nature of the package, and similar conditions. It is not always necessary to have the rolls 30 and 81 pinch the flap *f* in the manner described but the glue pot 74 may be so adjusted that it will come in contact with the flap *f* in advance of the roll 30 or in some other relationship to the latter roll. In order to facilitate this adjustment, the glue pot 74 is provided with a slide 90 that is mounted in a horizontal guideway formed in the arm 77 and this arm is slotted as indicated at 91 to receive a bolt projecting therethrough from the slide 90 and serving to clamp the glue pot in any adjusted position. The vertical limits of movement of the glue pot, and consequently

of the glue applying roll 81 can be varied by adjusting the bolt 86 in the post or rod 87. When the wrapper W is made of very stiff paper or other firm material it usually 5 is unnecessary to pinch the flap between the rolls 30 and 81 since this material is much less liable to sag or wrinkle and the movement of the folder bar 33 in the manner above described insures a tight wrapping.

10 When the flap f is very short it is, of course, necessary to adjust the parts 90 and 86 so that the roll 81 upon its downward movement will arrive at a point in advance of and below the position in which it is 15 shown in Fig. 1. It may be necessary also to substitute a new bracket for the bracket 31 so as to position the roll 30 more nearly opposite the roll 81. The construction provided by this invention is of special utility 20 where wrappers having short flaps are used, even though the parts are not adjusted so as to pinch the flap; in fact it is often difficult to glue a short flap satisfactorily without this mechanism. By using the 25 folder bar 33 and the operating mechanism therefor, the motion of this folder can be utilized to swing the flap against the roll 81, the motion of this roll being so timed that it will be moved down into the path in 30 which the flap is swung by the folder and then moved out of said path again. The folder 33 also performs the function of substantially closing the space between the tumble box and the chute 16. Considerable 35 space must be provided at this point in order to permit the longitudinal wrapper flap to swing into the proper position for the gluing operation. But when the package is forced out of the tumble box into 40 the chute, unless this space is closed, the rear flap which has already been folded on to the package sometimes flips up as the package is pushed out of the tumble box and is doubled back by the folding of the rear 45 flap. The folder 33 effectually prevents any such action by substantially closing the space between the tumble box and the chute when the package is forced out of the tumble 50 box into the chute.

55 It is obvious that this invention may take many forms and that many changes may be made in the details of construction without departing from the spirit or scope of the invention.

Having thus described my invention, what I claim as new and desire to secure by Letters Patent of the United States is:

1. In a wrapping machine, the combination with means for partially folding a 60 wrapper about an article leaving an unfolded wrapper flap extending therefrom, of devices for grasping said flap, and wrapper tensioning means mounted and operated independently of said devices and constructed and arranged to perform its wrap-

per tensioning operation by engaging with said flap between said article and the point at which the flap is grasped by said devices.

2. In a wrapping machine, the combination of means for partially folding a wrapper around a substantially unyielding article leaving an unfolded wrapper flap extending therefrom, and means for tensioning said flap to tighten the wrapper about the article while the entire article remains stationary and prior to the folding of said flap upon the article.

3. In a wrapping machine, the combination with means for partially folding a wrapper around an article, leaving an unfolded wrapper flap extending therefrom, of means for grasping said flap, a device operative to bear on the flap between said article and the point at which it is grasped by said means, and driven mechanism independent of said wrapper grasping means for moving said device to cause it to tension the wrapper.

4. In a wrapping machine, the combination with means for partly folding a wrapper around an article, leaving an unfolded wrapper flap extended therefrom, of a glue applying device mounted for movement into contact with said flap, means coöperating with said device to grasp said flap, a member mounted for movement into contact with said flap at a point between the article and the point at which the flap is grasped by said devices, and means for moving said member to cause it to tension the wrapper.

5. In a wrapping machine, the combination with means for partly folding a wrapper around an article, leaving an unfolded wrapper flap extending from said article and means for advancing the article to effect a further wrapping operation, of a folder mounted for movement across the path of advancement of said article and operative to swing said flap across the forward face of the article and to fold said flap on to said article upon the said advancing movement of the article.

6. In a wrapping machine, the combination with means for partly folding a wrapper around an article leaving an unfolded wrapper flap extending from said article and means for advancing the article to effect a further wrapping operation, of a folder mounted for movement across the path of advancement of said article and operative to swing said flap across the forward face of the article, and means for grasping said flap and holding it across the path of movement of said folder.

7. In a wrapping machine, the combination with a tumble box, means coöperating therewith to push an article to be wrapped into said tumble box thereby partially folding a wrapper around the article, operating mechanism for said tumble box and a chute

into which the article is ejected from said tumble box, of a device movable across the path of the ejecting movement of said article and operative to swing the unfolded 5 wrapper flap into position across the face of the article, and operating mechanism for said device.

8. In a wrapping machine, the combination with a tumble box, means coöperating therewith to push an article to be wrapped into said tumble box thereby partially folding a wrapper around the article, operating mechanism for said tumble box and a chute into which the article is ejected from said 10 tumble box, of a device movable across the path of the ejecting movement of said article and operative to swing the unfolded wrapper flap into position across the face of the article, operating mechanism for said 15 device, and a glue applying device positioned in the path in which said flap is moved by said device.

9. In a wrapping machine, the combination with a tumble box, means coöperating therewith to push an article to be wrapped into said tumble box thereby partially folding a wrapper around the article, operating mechanism for said tumble box and a chute into which the article is ejected from said 20 tumble box, of a device movable across the path of the ejecting movement of said article and operative to swing the unfolded wrapper flap into position across the face of the article, operating mechanism for said 25 device and means coöperating with said device to tension the flap.

10. In a wrapping machine, the combination with a tumble box, means coöperating therewith to push an article to be wrapped into said tumble box thereby partially folding a wrapper around the article, operating mechanism for said tumble box and a chute into which the article is ejected from said 30 tumble box, of a folder movable across the path of the ejecting movement of said article 35

cle into position to fold said flap on to the article when the article is ejected from the tumble box, and means for grasping said flap and holding it across the path of movement of said folder.

50

11. In a wrapping machine, the combination with a tumble box, means coöperating therewith to push an article to be wrapped into said tumble box thereby partially folding a wrapper around the article, operating mechanism for said tumble box and a chute into which the article is ejected from said tumble box, of a folder movable across the path of the ejecting movement of said article into position to fold said flap on to the article when the article is ejected from the tumble box, and means including a glue applying device operative to grasp said flap and hold it across the path of movement of said folder.

65

12. In a wrapping machine, the combination with a tumble box, means coöperating therewith to push an article to be wrapped into said tumble box thereby partially folding a wrapper around the article, operating mechanism for said tumble box and a chute into which the article is ejected from said tumble box, of a folder mounted for movement transversely of the path of the ejecting movement of said article into a position just above said path where it partially closes the space between the tumble box and said chute.

70

13. In a wrapping machine, the combination of mechanism for partially folding a wrapper around an article leaving an unfolded wrapper flap extending therefrom, and additional mechanism for acting on said wrapper flap to tighten the wrapper about the article while the article remains stationary, said additional mechanism including means for grasping the wrapper flap.

75

In testimony whereof I have signed my name to this specification.

AUGUSTUS HECK.
